[57] CLAIM

The ornamental design for a ceiling fan blade, as shown and described.

DESCRIPTION

FIG. 1 is a side, bottom perspective view of a ceiling fan blade showing my new design in full lines with the broken line showing of environmental association matter being for illustrative purposes only and forming no part of the claimed design;

FIG. 2 is an enlarged bottom view of the ceiling fan blade, the top view being a mirror image thereof;

FIG. 3 is an enlarged right side view thereof, the left-side view being a mirror image thereof;

FIG. 4 is an enlarged proximate end view thereof; and,

FIG. 5 is an enlarged distal end view thereof.
